James W. Benes
BY Frank Schraeder Jr.
ATTORNEY

UNITED STATES PATENT OFFICE.

ERNST F. ENGSTROM, OF MAYWOOD, AND JAMES W. BENES, OF HOLLYWOOD, ILLINOIS,
ASSIGNORS TO EVERHOT MANUFACTURING COMPANY, OF MAYWOOD, ILLINOIS, A
CORPORATION OF ILLINOIS.

TORCH.

Application filed June 20, 1925. Serial No. 38,432.

This invention relates generally to torches used particularly for heating branding and soldering irons and the like, and has among its objects the provision of a novel torch 5 which shall be adaptable for operation with various grades of fluid fuels such as gasoline and kerosene. To this end, is provided an adjustable needle valve co-operative with an adjustable Venturi tube for controlling the passage of air into the combustion chamber.

Another object of this invention resides in the provision of a novel combination shield and priming cup which is formed of a 15 single piece of sheet metal and which not only serves as a protection for the burner from cold air currents, but which affords a quicker preheating during the starting operation of the burner.

20 A further object of my invention resides in the novel construction and arrangement of the vaporizing chamber together with inlet and outlet passages for same and their relative position to the combustion chamber.

25 A still further object of the invention resides in the novel compact construction and arrangement of the burner which not only tends to enhance the efficient operation of same with various grades of fluid fuels, but 30 which renders the manufacture of same at a minimum of cost.

With these and other objects in view, my invention consists in the novel combination, construction, and arrangement of the parts 35 and members shown in the accompanying drawings, described in the following specifications and particularly pointed out in the appended claims.

Referring to the illustrations, which show 40 one embodiment of my invention, Fig. 1, is a side elevation of a torch embodying my invention and having the shield removed to show the exterior view of the burner.

Fig. 2, is a longitudinal cross section of 45 the burner;

Fig. 3, is a cross section taken on line 3—3 of Fig. 1, showing the annular vaporizing chamber;

Fig. 4, is a cross section taken on line

4—4 of Fig. 1, showing the rear view of the burner;

Fig. 5, is a cross section taken on line 5—5 of Fig. 1, showing the burner outlet;

Fig. 6, is an end elevation of the burner showing the retaining screws and bosses 55 for supporting the burner accessories;

Figures 7 and 8 are respectively longitudinal section and end elevation of my improved combined shield and priming cup.

Referring now more particularly to the 60 illustrations in Figures 1 to 6 inclusive, the burner, generally indicated by numeral 10, comprises a cast metallic tubular wall 11 having a central longitudinally disposed mixing and combustion chamber 12 with an open inlet end 12^A and an open outlet end 12^B. Near the outlet end 12^B, I provide an annular vaporizing chamber 13, which is formed within the annular wall formation 14 cast integrally with the combustion 70 chamber wall casing 11.

Cast integrally with the tubular combustion chamber casing 11, and extending parallelly and longitudinally therewith and on opposite sides thereof, are two tubular casings 15 and 16.

The fuel inlet passage 15^A within the casing 15 is in open communication at its forward end with the lower portion of the vaporizing chamber 13 and its rear end is inferiorly threaded to receive the fuel inlet pipe 17 which communicates with the fuel tank 18. The tank 18 is provided with the usual air pressure pump which is mounted within the tank but since same is not a part 80 of this invention it is not indicated on the drawing; the projecting pump hand wheel however, being shown and indicated by numeral 19.

The vaporized fuel passage 16^A within the casing 16 is in open communication at its forward end with the upper portion of the vaporizing chamber 13 and at its rear end is inferiorly threaded to receive the threaded end 20^A of a right-angular extension 20^B which is formed integrally with the tubular valve stem casing 20. The extension 20^B encloses a right angular passage 20^C the up-

per end of which communicates with the vaporized fuel passage 16^A and the lower end with the passage 20^D having an outlet opening 21^A in the plug 21 which is screw mounted into the end of the casing 20. The vaporized fuel discharge opening 21^A is controlled by a needle valve 22 which is fixed within the end of the screw threaded stem 23 having an operating hand wheel 24. The 10 threads upon the stem 23 co-operate with the interior threads of the tubular casing 20. A gland nut 25 and suitable packing 26 provide a tight connection around the stem 23. By turning of the hand wheel 24 a very fine 15 and accurate adjustment of the discharge opening 21^A is afforded.

It will be observed from Fig. 2, that the discharge end of the thread plug 21 is located just outside of the face of the rear end 20 12^A of the combustion chamber casing 11 and that a Venturi tube 27 is aligned therewith and movably supported by means of a set screw 28 within the end 12^A of the combustion chamber 12. The interior of the 25 Venturi tube 27 is formed to gradually converge toward the discharge end. It is now readily apparent that I have provided an 30 adjustably supported Venturi tube which is adjustably movable along the longitudinal axis of the fuel discharge by which the amount of air passing into the mixing and combustion chamber 12 may be varied to suit the kind and grade of fuel.

The front end of the burner is provided 35 with a pair of bosses 29 having openings or recesses 29^A adapted to receive the extensions 30 of various blow torch accessories such as a branding iron 31 or soldering tip.

Also the flame emitting end 12^B may be 40 provided with screws 32 for retaining accessories with extensions which fit directly into the end 12^B.

The end 12^B of the combustion chamber is also preferably provided with flame emitting 45 radially disposed openings 12^C which are located near the outer wall 14 of the vaporizing chamber 13.

The wind shield 33 is formed of one piece 50 of sheet metal having substantially flat sides 33^A with a depression 33^B in the bottom forming a priming cup adapted to receive a quantity of fuel through an opening 34 in the bottom of the combustion chamber near the end of the Venturi tube 27 for preheating 55 of the burner preliminary to starting operation. The top of the shield 33 is open as at 33^C and the end top portions are overlapped as at 33^D and either riveted or welded together at this point.

The vaporized fuel passage 20^C and the 60 vaporizing chamber 13 are provided with openings to permit cleaning of same, which openings are normally closed by threaded plugs respectively indicated by numerals 35 and 36.

The "clean out" plug 35 serves also to support the upper rear end of the wind shield 33 and the plug 36 is adapted to receive a screw 37 which rigidly supports the lower front end of the shield 33 between the 70 plug 36 and the torch support 38 which is made of a bent flat bar to form legs 38^A.

From the above description and the attached illustrations it will be apparent that the fuel is passed under compression from the tank 18 through the pipe 17 and passage 15^A into the vaporizing chamber 13 where it is thoroughly vaporized and then passed into the return passage 16^A and through the 80 passage 20^C for discharge through the needle valve controlled opening 21^A through the Venturi tube 27 into the combustion chamber 12. As above stated the relative position of the Venturi tube 27 along the longitudinal axis of the discharge opening 21^A will determine the relative amount of air and fuel 85 passed into the combustion chamber 12, thus adapting the operation of the burner to not only gasoline but also heavier fluid fuels, such as kerosene. It may also be stated that the integral tubular members 15 and 16 due to their proximity to the combustion chamber will materially tend to increase the vaporization of the fuel preliminary to its discharge into the combustion chamber 12. 90

The hand wheel 24 for the fuel needle valve comprises a circular rim 24^A having a single integrally cast spoke 24^B terminating at the hub 24^C also cast integrally with the arm or spoke 24^B. It will be observed that the fuel inlet pipe 17 extends through the annular opening 24^D of the hand wheel for the purpose of presenting a positive stop for the hand wheel 24 when the spoke or arm 24^B engages the side thereof, thus positively preventing over tightening of the needle valve in closing position. This arrangement overcomes the possibility of stripping the threads on the needle valve stem 23 or injuring the needle by over tightening which often occurs when a positive stop is not provided. A nut 24^E is provided on the end of the stem 23 to retain the handle 24 thereto. 105

Due to the single spoke construction less 110 heat is conducted from the stem to rim to wheel making a cooler handling valve wheel 24.

I claim:

1. In a torch of the character described, and in combination, a burner for said torch adapted to receive fluid fuel under pressure, said burner having a combustion chamber, a shield rigidly supported on said burner and embracing said combustion chamber, said combustion chamber having a fluid fuel outlet, and a priming cup depressed in said shield adapted to receive fluid fuel from said outlet for preheating of said burner and combustion chamber. 120

125

130

2. In a blow torch, and in combination, a burner for said torch having a combustion chamber and a fluid fuel vaporizing chamber, a shield supported on said burner and embracing said combustion chamber and said vaporizing chamber, said combustion chamber having a fluid fuel outlet, and a

priming cup depressed in the bottom of said shield adapted to receive fluid fuel from said outlet for preheating of said burner. 10

In witness whereof we affix our signatures.

E. F. ENGSTROM.
JAMES W. BENES.
